Attorneys.

UNITED STATES PATENT OFFICE.

CHARLES W. H'DOUBLER, OF RACINE, WISCONSIN.

SEWING-MACHINE PULLEY.

1,380,715.

Specification of Letters Patent. Patented June 7, 1921.

Application filed March 26, 1920. Serial No. 368,970.

To all whom it may concern:

Be it known that I, CHARLES W. H'DOUBLER, a citizen of the United States, and resident of Racine, in the county of Racine 5 and State of Wisconsin, have invented new and useful Improvements in Sewing-Machine Pulleys, of which the following is a description, reference being had to the accompanying drawings, which are a part of 10 this specification.

The present invention relates to certain new and useful improvements in electrically driven sewing machines, and refers more particularly to the friction pulley employed 15 to drivingly connect the motor armature shaft with the sewing machine drive or hand wheel.

One object of this invention is to provide an electrically driven sewing machine in 20 which the armature shaft of the motor has a pulley mounted on one end thereof and in frictional engagement with the hand or drive wheel of the machine, the pulley being slidably but non-rotatably mounted on the 25 armature shaft whereby the same will readily compensate for any irregularities in the machine hand or drive wheel.

A further object of this invention is to provide a friction pulley of the class described including two spaced apart disks 30 and adjustable with respect to each other, whereby the same may be adjusted to compensate for wear and to also adapt the same to drive wheels of various diameters.

A still further object of the invention is to provide a friction pulley for an electrically driven sewing machine which is of simple construction, is strong and durable 35 and is well adapted for the purpose described.

With the above and other objects in view which will appear as the description proceeds my invention resides in the novel construction, combination of parts substantially as hereinafter described and more particularly defined by the appended claims, it being understood that such changes in the precise embodiment of the herein disclosed invention may be made as come within the 45 scope of the claims.

In the accompanying drawing I have illustrated two complete examples of the physical embodiment of my invention constructed according to the best modes I have

so far devised for the practical application 55 of the principles thereof, and in which:

Figure 1 is a side view of a rear portion or tubular standard of a sewing machine equipped with my improved pulley, parts being broken away and in section to more 60 clearly illustrate the construction thereof.

Fig. 2 is a view taken on the line 2—2 of Fig. 1, and

Fig. 3 is a sectional view taken through a slightly modified form of pulley. 65

Referring now more particularly to the drawing, numeral 5 indicates a tubular supporting standard of a sewing machine, 6 a longitudinally extending drive shaft journaled in the overarm (not shown) of the machine, and 7 a drive or hand wheel fixed to the portion of the shaft 6 projected outwardly of the standard 5. As is usual in sewing machine constructions, the shaft 6 is connected with the usual mechanism of the 70 machine for driving the same upon rotation, and the shaft 6, in the present instance is rotated by means of an electrical motor 8 having its armature shaft 9 connected with the hand wheel by means of an improved form of friction pulley now about to be described. 75

My improved form of friction pulley includes a sleeve 10 formed at its inner end with a flange 11 and having its outer end 80 exteriorly threaded, as at 12, to receive an adjusting securing nut 13. Mounted upon the sleeve 10 are two complementary disks 14 and 15 having their peripheries oppositely curved, as at 16, to provide an annular groove in which the periphery of the wheel 7 runs. The disk 14 is tightly pressed 85 on the sleeve 10 and is engaged against the flange 11, and the disk 15 is slidably mounted upon the sleeve, but held from rotation with 90 respect thereto by means now to be described. 95

A flange plate 17 is slidably mounted upon the sleeve 10 and is secured to the outer face of the disk 15 by means of screw members 100 18, which screw members have their inner ends reduced and plain to form guide pins 19 which are slidable within apertures 20 formed in the disk 14 and flange 11. From this construction, it will be readily seen that 105 the disk 15 may be readily moved toward and away from the disk 14 but is held from rotation with respect thereto by means of

the guide pins 19 formed integral with the screws 18. The disks 14 and 15 are retained in spaced relation by means of an extensile spring 21 coiled about the sleeve 10 between 5 the disks, and the action of said spring is restrained by means of a stronger extensile spring 22 coiled about the sleeve 10 intermediate the nut 13 and flange plate 17.

With this construction the peripheries 16 10 of the disks 14 and 15 are at all times held in frictional engagement with the periphery of the machine drive wheel 7, and when the peripheries of the disk become worn, such wear is compensated by tightening the 15 nut 13. The nut 13 is preferably knurled for convenience in adjusting the same without the use of tools of any kind.

As the drive wheels of sewing machines in general use do not run perfectly true, 20 the sleeve 10 is slidably but non-rotatably mounted upon the armature shaft so that the same will readily give and follow any irregularity in the run of the fly wheel 7. In the present instance I have illustrated 25 the sleeve 10 as being slidably splined to the shaft 9 by a key member 23, but it will be readily understood that any other means may be employed.

In Fig. 3 I have illustrated a slightly 30 modified form of my invention in which the disks 14 and 15 are held in spaced relation by means of a yieldable or resilient member 24 which takes the place of the spring 21, and the disk 15 being retained 35 from rotation with respect to the sleeve firmly clamping the disks 14 and 15 and the spacer 24 between the flange 11 and flange plate 17. In this form of my invention the spring 22 is eliminated and the nut 40 13 abuts directly against the plate 17. As the disk members 14 and 15 wear, the wear is compensated for by tightening the nut 13 which compresses the spacer 24 and forces it partly into the annular groove formed 45 by the curved surfaces 16 as will be readily apparent.

What I claim as my invention is:

1. A device of the class described, comprising a pair of opposed disks, yieldable means disposed between the disks to normally tend to urge the same apart, and means yieldably resisting the movement apart of the disks under the action of said first mentioned means.

55 2. A device of the class described, comprising a sleeve, a pair of disks on said sleeve and having their peripheries oppositely curved to form an annular groove, one of said disks being rigidly fixed to said 60 sleeve, a flange plate mounted on said sleeve and engaging the other of said disks, and means for retaining said flange plate and disk engaged thereby in the proper position relative to the other disk.

65 3. A device of the class described, com-

prising a sleeve having an annular flange on one end thereof, a pair of disks on said sleeve and having their peripheries oppositely curved to form an annular groove, one of said disks being fixed to said flange, 70 a flange plate mounted on said sleeve and having the other of said disks secured thereto, and means for retaining said flange plate and disk carried thereby in the proper position with respect to the other disk. 75

4. A device of the class described comprising a sleeve having an annular flange on one end thereof, a pair of disks on said sleeve, one of said disks being fixed with respect to said flange, a flange plate slidably but non-rotatably mounted on the sleeve and having the other disk fixed with respect thereto, yieldable means retaining said disk in spaced relation, and means for retaining said flange plate upon the sleeve. 80 85

5. A device of the class described comprising a sleeve having an annular flange on one end thereof, a pair of disks on said sleeve, one of said disks being fixed with respect to said flange, a flange plate slidably but non-rotatably mounted on the sleeve and having the other disk fixed with respect thereto, 90 spring means normally urging the disks apart, and means engageable with said flange plate to resist the force of said spring 95 means.

6. A device of the class described comprising a sleeve having an annular flange on one end thereof, a pair of disks on said sleeve, one of said disks being fixed with respect to said flange, a flange plate slidably but non-rotatably mounted on the sleeve and having the other disk fixed with respect thereto, 100 an extensile spring confined between the disks and urging the same to spaced relation, and a second spring engageable with said flange plate to resist the first mentioned spring. 105

7. A device of the class described, comprising a sleeve having an annular flange on one end thereof, a pair of disks on said sleeve, one of said disks being fixed with respect to said flange, a flange plate slidably but non-rotatably mounted on the sleeve and having the other disk fixed with respect thereto, 110 an extensile spring confined between the disks and urging the same apart, and a second spring of greater force than the first mentioned spring and engaging said flange plate to restrain the action of the first mentioned 115 120

8. A device of the class described, comprising a sleeve having an annular flange on one end thereof, a pair of disks on said sleeve, one of said disks being fixed with respect to said flange, a flange plate slidably but non-rotatably mounted on the sleeve and having the other disk fixed with respect thereto, 125 an extensile spring confined between the disks and urging the same 130

apart, a second spring engaging said flange plate to restrain the action of the first mentioned spring, and means for adjusting the tension of said second spring.

5 9. A device of the class described, comprising a sleeve, a pair of disks on the sleeve, one of said disks being fixed with respect to the sleeve and the other being slideable

thereon, a guide pin carried by one of said disks and engageable in an aperture in the 10 other disk, and means adjustably maintaining the disks in spaced relation.

In testimony whereof, I affix my signature.

CHARLES W. H'DOUBLER.
